WRENCH

Pierre Porte, Viroflay, France

Application August 18, 1930, Serial No. 476,172,
and in France August 20, 1929

1 Claim. (Cl. 81—161)

This invention relates to improvements in wrenches, especially wrenches for turning nuts and for doing similar work, the object of the invention being to provide an improved wrench 5 of this kind which is simple in construction, is strong and durable, which can be readily operated and is not likely to get out of order.

With the above and other objects in view, the invention consists in the construction, combination and arrangement of devices hereinafter described and claimed.

In the accompanying drawing

Figure 1 is a side elevation of a wrench constructed and arranged in accordance with this 15 invention.

Figure 2 is a similar view of a modified form of the wrench.

Figure 3 is a similar view of another modified 20 form of the wrench.

Figure 4 is a transverse sectional view of the form of the wrench shown in Figure 1.

Figure 5 is a detail longitudinal sectional view of the cylindrical slider.

My improved wrench comprises a jaw 1 having 25 a shank 2 which presents two opposite flat sides and two opposed convex surfaces 3 which are provided with screw threads. A jaw 4 is arranged to slide on the shank toward and from the jaw 1 and is provided with a frame 18 which 30 is provided with a transverse opening 18^a and a groove 16 in one longitudinal side of said opening extending thereacross and a recess 17 forming a notch at the opposite side of said opening.

35 A cylindrical slider 8 is arranged in said opening and has interior interrupted threads 13, 14 to cooperate with the threads of the shank when the slider is in one position and to cause the jaw to move so as to disengage the threads of the shank when the slider is in another position. The slider has a spur 15 on its circumference movable across the groove 16 and engageable in the notch 17 of the frame or casing to stop rotation 40 of the slider so that the latter may execute an almost complete rotation.

At the ends of the opening 18^a the frame 18 is 45 provided on opposite sides with crowns 5, 10 which form lateral enlargements of said frame. Coil springs 6, 9 are at opposite ends of the slider and bear between the same and the ends of the opening, and exert from each end of the slider a pressure such that if the locking is not effected during the first partial rotation it may be caused during the second partial rotation, and so 50 that engagement of the slider in the threads of the shank may be assured by a light compression of the springs in the event that the threads of the slider should not immediately engage those of the shank.

60 In the form of the invention shown in Figure

1, an extension sheath 11 is provided for the outer end portion of the shank and which extends from the frame 18 and is provided in one side with a longitudinal slot 19. A pin 20 projects from one side of the shank and is arranged 65 to move longitudinally in said slot and is provided at its outer end with a knob 21 which can be grasped by the user of the wrench for effecting the movement of the jaw 4 with one hand only.

In the form of the invention shown in Figure 2, the sheath 11 of Figure 1 is dispensed with and the outer end of the shank is somewhat widened and rounded to facilitate the grasping thereof.

In the form of the invention shown in Figure 3, the movable jaw 24 operates in an open notch with which the first jaw 121 is provided, said jaw having in addition to the handle shank 122 a shank member 33 having flat opposite sides and 80 also having convex threaded edges and the slider 28 operates in an opening directly in the movable jaw 24 which is in all respects identical with the opening in the frame of the jaw 4 shown in Figures 1 and 2 and hereinafter described.

Having thus described my invention, I claim:

A wrench for a nut comprising a jaw having a shank presenting two opposed flat sides and two opposed convex surfaces connecting the flat sides, and provided with screw threads, a jaw having a frame which slides on the said shaft and is provided with a transverse opening, a recess in one longitudinal side of the opening forming a notch and a groove extending across the opposite longitudinal side of said opening, a cylindrical slider arranged in said opening and presenting threads interrupted to cooperate with the threads of the said shank when the slider is in one position, and to disengage the threads of the shank when the slider is in another position, said slider having a spur on its circumference movable across the groove of the said side of the opening, and engageable in the notch of the frame to stop rotation of the slider, so that the slider may execute an almost complete rotation, 95 springs exerting from each end of the slider a pressure such that if the locking is not affected during the first partial rotation it may be completed during the second partial rotation, and so that engagement of the slider in the threads of the said shank may be assured by a light compression of the springs in the event that the thread of the said slider should not immediately engage those of the shank.
